UNITED STATES PATENT OFFICE.

JAMES V. WASHBURN, OF SYRACUSE, NEW YORK.

ENVELOPE-OPENING MACHINE.

Application filed October 13, 1920. Serial No. 416,665.

To all whom it may concern:

Be it known that I, JAMES V. WASHBURN, a citizen of the United States, and a resident of Syracuse, in the county of Onondaga and State of New York, have invented a certain new and useful Envelope-Opening Machine, of which the following is a specification.

This invention relates to envelope opening machines of the type set forth in my Patent, No. 1,265,844, issued May 14, 1918; and has for its object a particularly simple and efficient means for supporting and adjusting the shear plate and also particularly simple and efficient means for supporting the lubricating and compression rolls. The invention consists in the novel features and in the combinations and constructions hereinafter set forth and claimed.

20 In describing this invention, reference is had to the accompanying drawings in which like characters designate corresponding parts in all the views.

Figure 1 is a plan view of my envelope opening machine, the housing for the lubricating tool being omitted.

Figure 2 is a front elevation thereof, the housing for the lubricating roll being shown in section and also the housing for the spring which actuates the cutter roll in one direction being also shown in section.

Figure 3 is an end elevation of this machine, the housing for the spring of the cutter being omitted.

5 Figure 4 is a vertical sectional view on line 4-4, Fig. 2.

Figure 5 is a sectional view on line 5—5, Fig. 2.

Figure 6 is an end elevation looking to the left in Fig. 1.

This envelope opening machine comprises, generally, a base which is elongated in

5 general form and formed with uprights near its ends, and an upright intermediate of its ends, a cutter movable about an axis and having axles journaled in uprights on the base, a shear plate mounted on the first mentioned uprights and on the intermediate upright in front of the cutter and being un-
0 attached to the uprights at its ends and merely resting thereon, means associated with the intermediate upright for holding the shear plate in position and also for ad-justing it toward and from the cutter, and
5 means mounted on the axles of the cutter for supporting a lubricating roll and a

compression roll. Some of the foregoing features may however, be omitted.

1 designates the base which may be of any suitable form, size and construction, it being here shown as formed with a recess extending inwardly from the rear side thereof for holding a receptacle 2 which receives the clippings, this recess making the base elongated U-shaped so that it has end portions 3 and front transverse bar 4 connecting the ends 3. 60 65

5 are uprights rising from the front portions 4 of the base and spaced apart thereon. 6 is the intermediate upright rising from the portion 4. 7 is a cutter here shown as cylindrical and having axles 8 journaled in uprights 9 and 10 rising from the rear ends of the end portions 3 of the base. The cutter here shown is of the form shown in my Patent No. 1,265,844 issued May 14, 1918, but in so far as this invention is concerned, may be of any suitable form, size and construction.

11 is the shear plate mounted on the uprights 5 and 6 and resting at its ends on the uprights 5 and being unattached thereto and also resting on the intermediate upright 6 adjustably secured thereto. The shear plate as here shown is secured to the intermediate upright by means of a block 12 located in a vertical slot 13 formed in a rearwardly extending portion of the upright 6 which portion overhangs the receptacle 2 the slot opening through upper and lower faces of the extension and also through the rear face thereof, the block 12 having shoulders 14 at its lower end engaging the under side of the overhanging portion 15.

portion of the upright 6 on opposite sides of the slot 13, means for clamping the shear plate to the block, and means for adjusting the block along the slot 13 and holding it in its adjusted position. The clamping means as here shown comprises a screw 15 extending through the shear plate from the upper side thereof and threading in the block 12; and the means for holding or determining the position of the block along the slot 13 and hence the position of the shear plate relatively to the cutter, as here illustrated, comprises a set screw 16 threading in the intermediate upright, that is, in the front side thereof and thrusting against the block 13. Thus by loosening both screws 15, 16 the shear plate can be moved toward or from the cutter and when in its adjusted 100 105 110

position the screw 15 tightened and the screw 16 turned inwardly until it abuts against the block to prevent sliding thereof and of the shear plate away from the cutter.

5 Springs 17 are usually attached to the ends of the shear plate and to the frame and tend to pull the plate toward the cutter.

18 and 19 designate respectively, a lubricating roll cooperating with the cutter 7

10 and a compression roll overlying the shear plate, these rolls are here illustrated as having axles 20, 21 at their ends, the axles 20 of the lubricating roll being journaled in upwardly extending arms 22 of brackets 23

15 pivotally mounted on the axles 7 of the cutter adjacent the ends of the cutter and the axles 21 of the compression roll 19 journaled in forwardly extending arms 24 of said brackets, said arms 24 lying on the shear

20 plate and having extensions 25 extending in front of the roll and constituting guides for the envelope being passed between the shear plate and the roll to the cutter.

These extensions 25 have inwardly extending portions extending in front of the ends of the rollers and outwardly extending ends 27 arranged to engage the end edges of the envelope.

28 is a housing enclosing the lubricating roll and resting on the brackets, this housing having end walls 29 formed with openings as slots 30 which receive the axles 20 of the lubricating roll, said end walls lying outside of the upwardly extending arms 22

35 of the brackets 23. The housing is also formed with a shield 31 on the rear side thereof enclosing the rear portion of the cutter 7 and resting at its ends on the brackets 22. Owing to the arrangement of the housing it is readily removable for the purpose of applying a lubricant to the lubricating roll 18, it being understood that this roll rests on the periphery of the cutter 7.

The cutter 7 is moved about its axis in one direction by a suitable handle 32 mounted on one of the axles 7 of the cutter; and in the other direction by a spring 33 connected at one end to the other axle of the cutter, and at its other end to the frame. This

40 spring is enclosed in a suitable housing 34.

In operation, the shear plate is adjusted by loosening the screws 15 and 16 and sliding the shear plate and block 12 to the desired position relatively to the cutter 7 and the screws again tightened.

45 The envelope to be opened by having one edge thereof clipped off is laid on the shear plate 11 and passed under the compression roller until the edge to be clipped off is against the cutter.

The brackets 22 are movable about the axles 8 of the cutter as the compression roll is lifted by the envelope. The handle 32 is then pulled outwardly against the action of the spring 33 causing the cutter to

clip off the edge of the envelope and during this operation the lubricating roll is turned about its axis.

This envelope opening machine is particularly advantageous in that it consists of few parts which are so constructed and arranged so that the machine is particularly economical in manufacture.

What I claim is:

1. An envelope opening machine comprising a base formed with uprights, a rotary cutter having axles journaled in the uprights, a shear plate mounted on the base in front of the cutter, a pair of arms mounted on the axles of the cutter and extending forwardly therefrom, and a roller having axles at its ends journaled in said arms, the roller resting on the shear plate, substantially as and for the purpose described.

2. An envelope opening machine comprising a base formed with uprights, a rotary cutter having axles journaled in the uprights, a shear plate mounted on the base in front of the cutter, a pair of arms mounted on the axles of the cutter and extending forwardly therefrom, and a roller arranged above the shear plate and having axles at its ends journaled in said arms, said arms having extensions located in front of the roller to form guides for the envelope, substantially as and for the purpose specified.

3. An envelope opening machine comprising a base formed with uprights, a rotary cylinder cutter having axles journaled in the uprights, a shear plate mounted on the base in front of the cutter, a pair of arms mounted on the axles of the cutter and extending forwardly therefrom, and a roller overlying the shear plate and having axles at its ends journaled in said arms, said arms having inwardly offset extensions located in front of the roller, and having forwardly bent ends constituting guides in front of the roller for the envelope, substantially as and for the purpose set forth.

4. An envelope opening machine comprising a base formed with spaced apart uprights, a rotary cutter having axles journaled in the uprights, a shear plate mounted on the base in front of the cutter, a pair of brackets mounted on the axles of the cutter and having upwardly extending arms and a lubricating roll for the cutters having axles journaled in said upwardly extending arms of the brackets, substantially as and for the purpose described.

5. An envelope opening machine comprising a base formed with spaced apart uprights, a cylindrical cutter having axles journaled in the uprights, a shear plate mounted on the base in front of the cutter, brackets mounted on the axles of the cutter and having upwardly extending arms and also forwardly extending arms extending in front of the cutter, a lubricating roll hay-

ing axles journaled in the upwardly extending arms and a compression device overlying the shear plate and supported at its ends by the forwardly extending arms, substantially as and for the purpose specified.

6. An envelope opening machine comprising a base formed with spaced apart uprights, a cylindrical cutter having axles journaled in the uprights, a shear plate mounted on the base in front of the cutter, brackets mounted on the axles of the cutter and having upwardly extending arms and also forwardly extending arms extending in front of the cutter and overlying the shear plate, a lubricating device supported at its ends by the upwardly extending arms and a compression device overlying the shear plate and supported by the forwardly extending arms, the forwardly extending arms having extensions in front of the compression device, and constituting guides for the envelope, substantially as and for the purpose set forth.

7. An envelope opening machine comprising a base having uprights, a cutter movable about an axis and having axles journaled in the uprights, the lubricating device having axles at its ends, means for supporting the axles of said roll, and a casing enclosing the roll and having openings in its end walls for receiving the axles of the lubricating device, substantially as and for the purpose described.

8. An envelope opening machine comprising a base having uprights, a cutter movable about an axis and having axles at its ends journaled in the uprights, a lubricating device arranged above the cutter and having axles at its ends, brackets located at the opposite ends of the cutter and having upwardly extending arms formed with openings for the axles, and a housing for the lubricating device having slots in its end walls for receiving the axles of the lubricating device, the housing resting on the brackets, substantially as and for the purpose specified.

9. An envelope opening machine compris-

ing a base having uprights, a cutter movable about an axis and having axles at its ends journaled in the uprights, a lubricating device arranged above the cutter and having axles at its ends, brackets located at its opposite ends of the cutter and having upwardly extending arms formed with openings for the axles, a housing for the lubricating device having slots in its end walls for receiving the axles of the lubricating device, the housing resting on the brackets, and having a shield on the rear side thereof enclosing the rear portion of the cutter, substantially as and for the purpose set forth.

10. An envelope opening machine comprising a base formed with uprights, a cutter movable about an axis and having axles journaled in the uprights, a lubricating device supported above the cutter and having axles at its ends, supports for the axles, and a housing for the lubricating device mounted on the supports and having a shield on the rear side thereof enclosing the rear portion of the cutter, substantially as and for the purpose described.

11. An envelope opening machine comprising a base formed with uprights, a cutter movable about an axis having axles journaled in the uprights, a shear plate mounted on the base in front of the cutter, brackets mounted on the axles of the cutter, and having upwardly extending arms and forwardly extending arms overlying the shear plate, a lubricating device having axles supported at its ends by the upwardly extending arms, a compression device supported at its ends by the forwardly extending arms, a housing enclosing the lubricating device, and a housing for the lubricating device, the housing having a rearwardly extending shield enclosing the rear portion of the cutter, substantially as and for the purpose specified.

In testimony whereof, I have hereunto signed my name, at Syracuse, in the county of Onondaga, and State of New York, this 5th day of October, 1920.

JAMES V. WASHBURN.
